UNITED STATES PATENT OFFICE.

JOHN T. O'BRIEN, OF PHILADELPHIA, PENNSYLVANIA.

INTERIOR AND EXTERIOR SCAFFOLDING.

SPECIFICATION forming part of Letters Patent No. 295,579, dated March 25, 1884.

Application filed October 25, 1883. (No model.)

To all whom it may concern:

Be it known that I, JOHN T. O'BRIEN, of the city and county of Philadelphia, in the State of Pennsylvania, have invented certain new and useful Improvements in Interior and Exterior Scaffolding.

The following is a specification of my improvements, reference being had to the accompanying drawings.

10 Figure 1 is a view in perspective of a scaffold embodying the invention. Fig. 2 is a horizontal cross-section through the base of the upright. Figs. 3 and 4 are vertical longitudinal sections through the pieces which compose the feet of the uprights. Fig. 5 is a top or plan view of one of the locking-pieces by which the feet are secured. Fig. 6 is a view in perspective, and on an enlarged scale, of the box or casting which forms the base of the upright, and receives the removable feet. Fig. 7 is a similar view of the bracket which is attached to the upright; and Fig. 8 is a side elevation of the upright when adapted to rest upon a staircase.

25 The object of my invention is to provide a system of portable scaffolding which shall be readily erected and removed, secure when in position, and capable of adaptation to the varying requirements of use, especially in the interior of houses, where limited space and difficulties of obtaining a secure footing for the uprights frequently prevent the erection of ordinary scaffolds without marring the walls or floors through the use of nails, &c.

35 To these ends my improvements consist in the following combinations of parts: The uprights A are constructed of ordinary scantling; but the sides, instead of being flush, are longitudinally rabbeted or grooved, as shown at

40 a . At intervals holes b are formed in each transverse direction through the uprights, the series upon one side being "staggered" or alternate with respect to the series at right angles thereto. The lower end of the upright

45 A , I prefer to construct of metal to avoid wear, a convenient form of device for that purpose being a cast-iron base-piece, B , in which are grooves a' , forming continuations of the grooves a . The lower end of the upright A is fitted

50 securely in the iron base-piece B , which may be considered as practically one piece therewith. Vertical slots c at right angles to one

another are formed in the base-pieces B , and extend through the lower end of the upright A , to receive the feet. The feet C are preferably 55 constructed of wood, and provided with central cast-iron locking-pieces D , by means of which the opposite members of each pair are secured together permanently and the two pairs locked at right angles in the base-piece 60 B . These locking-pieces consist of plates d , having flanges e , adapted to fit closely in the grooves a' on opposite sides of the base-plate B when the central portion of the plate d is inserted in the slot c . The extreme ends of 65 the plate d project into the feet C , and are secured thereto by horizontal bolts f . The feet, however, may be made of iron, forming, together with the locking-piece, one casting. Vertical slots m n are formed in the centers of 70 the plates d , the slot m extending upward from the bottom of one plate, and the slot n downward from the top of the other, so that when the two pairs of feet are united at right angles to one another these slots permit them to 75 come together in the same horizontal plane. The brackets F are cast in the form shown in Fig. 7, and slide freely vertically in the grooves a of the uprights, being secured at any desired height by means of bolts g , passing through the 80 holes in the latter, and provided with nuts h . The bolt-holes l in the bracket may, if desired, be arranged at irregular distances to obtain a large range of adjustments. The base-pieces B , brackets F , and locking pieces D are 85 preferably constructed of malleable iron.

When it is desired to erect the scaffolding, the locking-piece D of the pair of feet shown in Fig. 3 is first inserted in one slot c of the base-piece, the flanges e on either side fitting in the 90 grooves a' . The locking-piece D of the other pair of feet (shown in Fig. 4) is inserted similarly in the other slot c , and by reason of the two slots m and n coming together, both pairs of feet are permitted to slide home in the slots 95 c . As many uprights as are required having been thus erected, the brackets F are secured at the proper height by means of the bolts and nuts g h , and the staging is then laid across the brackets, in the usual manner.

When the upright is to be rested upon a staircase, I erect it in the following manner: Only one pair of feet is inserted in the slot c , and two inverted brackets F are then secured

at different heights in the line of ascent of the steps, as shown in Fig. 8, other brackets being used as before to support the staging.

I am of course aware that the use of adjustable brackets is not new, and I therefore do not desire to claim such use, except in combination with the peculiarly-formed uprights and other elements more particularly referred to herein-after. The important features of construction in these uprights are the grooves upon their several faces, which permit the securing of both brackets and feet in the simplest and most efficient manner, the former being held firmly by a single bolt, and the latter requiring no bolt or similar fastening whatever.

I claim—

1. The combination, with the upright A, having longitudinal grooves *a* upon its sides

and slots *c* at its base, of the feet C and locking-piece D, said locking-piece being adapted 20 and arranged with reference to the said grooves and slots substantially as set forth.

2. The combination, with the upright A, having longitudinal grooves *a* upon its sides and slots *c* at its base, of the feet C, having a 25 locking-piece, D, adapted and arranged with reference to said grooves and slots substantially as set forth, and the bracket-pieces F, adjustable vertically in said grooves, whereby the supports of the upright may be arranged 30 at different heights on opposite sides of the upright, as and for the purposes specified.

JOHN T. O'BRIEN.
